BARBER CHAIR OR SIMILAR ARTICLE

Nicholas S. Kategianis, Chicago, Ill., assignor to Emil J. Paidar Company, Chicago, Ill., a corporation of Illinois

Filed Jan. 2, 1962, Ser. No. 68,145

Term of patent 14 years

(Cl. D15—3)

FIGURE 1 is a perspective view of a barber chair showing my design.

FIGURE 2 is a front elevational view of one of the chair arms, the remaining chair portion having been omitted for convenience of illustration.

The inner face of the chair arm is substantially plain and unornamented.

The dominant feature of my design resides in the portion shown in full lines on the drawing.

I claim:

The ornamental design for a barber chair or similar article, as shown and described.
